US0D1072683S

(12) **United States Design Patent** (10) Patent No.: **US D1,072,683 S**
(45) Date of Patent: ** Apr. 29, 2025

(54) **MUFFLER FOR MOTORBIKES**

(71) Applicant: **Igor Akrapovic**, Ljubljana (SI)

(72) Inventors: **Igor Akrapovic**, Ljubljana (SI); **Ermin Kosovel**, Zgornje Gorje (SI); **Dorian Tomažin**, Krško (SI)

(**) Term: **15 Years**

(21) Appl. No.: **35/520,843**

(22) Filed: **Mar. 29, 2024**

(80) **Hague Agreement Data**

Int. Filing Date: **Mar. 29, 2024**

Int. Reg. No.: **DM/236760**

Int. Reg. Date: **Mar. 29, 2024**

Int. Reg. Pub. Date: **May 10, 2024**

(30) **Foreign Application Priority Data**

Oct. 5, 2023 (EM) 015036049-0001

(51) **LOC (15) Cl.** **12-16**

(52) **U.S. Cl.**

USPC **D12/194**

(58) **Field of Classification Search**

USPC D12/114, 110, 194; D15/5
CPC .. F01N 2590/04; F01N 2340/04; F01N 13/08;

F01N 13/082; F01N 13/10; F01N 13/20

See application file for complete search history.
